METHOD OF AND APPARATUS FOR TRIMMING TOP LIFTS OF HEELS

Norwood H. Knowlton, Rockport, Mass., assignor to United Shoe Machinery Corporation, Paterson, N. J., a corporation of New Jersey

Application January 18, 1932, Serial No. 587,184

16 Claims. (Cl. 12—88)

This invention relates to methods of and apparatus for trimming top lifts of heels. The invention is herein illustrated as embodied in a trimming machine the general organization of which is similar to that illustrated in Letters Patent of the United States No. 1,724,205, granted August 13, 1929, on my application. The trimming cutter shown in that patent is provided with skewed cutting edges that operate without producing a "rag" or fuzz at the attaching faces of leather top lifts, but because of the greater cost of such cutters due to the skewed arrangement of the cutting edges cutters having non-skewed cutting edges, as herein illustrated, are more generally used. The invention is herein disclosed, by way of illustration, with particular regard to problems encountered in trimming the top lifts of covered heels in the manufacture of which it is desirable to blend the profiles of the top lifts with those of the heel-covers.

When trimming the top lift of a covered heel, it is of primary importance to avoid damaging the cover, and when, as herein illustrated, the trimmed periphery of a top lift is to be flush with a previously applied cover on the body of the heel, one problem is to trim the entire thickness of the top lift without permitting the trimming cutter to scrape or otherwise mar the heel-cover. To insure satisfactory results with a trimming cutter of the type herein illustrated, the width or thickness of the cutter should be greater than the thickness of the top lift and the trimming cut should extend to the plane of the attaching face of the top lift but not beyond that plane on the side occupied by the heel-cover. The difficulty in trimming to but not beyond the plane mentioned is due largely to the fact that, notwithstanding the common practice of grading top lifts, within arbitrary limits of variation, according to their thicknesses, the thicknesses of top lifts having the same grade marking are not exactly uniform, particularly those of leather top lifts.

When a leather top lift is attached to a heel, its flesh side is toward the heel, and because of the contiguous relation between the top lift and the body of the heel, it has heretofore been difficult if not impossible, with a cutter of the type herein illustrated, to trim the flesh side of the top lift without leaving a "rag" or fuzz that mars the appearance of the finished product. For this reason, some manufacturers of covered heels use another type of trimming machine in which the cutter rotates about an axis substantially parallel to the plane of the tread-face of the top

lift and operates with a series of chopping cuts that progress from the attaching face toward the tread-face, since a cutter that operates on that principle leaves little or no rag or fuzz at the attaching face. Nevertheless, a cutter of that type is incapable of beveling the margin of the tread-face and is also incapable of forming a circumferential bead on the periphery of the top lift. On the other hand, a cutter of the type herein illustrated will not only trim the periphery of a top lift but will also bevel the margin of the tread-face and may also, if suitably formed, cut a bead on the periphery, since it cuts lengthwise rather than crosswise of the periphery.

In view of the conditions above described, an object of the present invention is to provide improvements in methods of and apparatus for trimming attached top lifts, to the end that their peripheries may be trimmed without forming any rag or fuzz on their attaching faces and without damaging the heels even when trimming the top lifts flush with the heels.

Accordingly, in one aspect, the invention provides an improved method of trimming attached top lifts which consists in maintaining the attaching face of an attached top lift flush with one cutting boundary of a trimming cutter that cuts lengthwise of the periphery of the top lift, and bracing the projecting margin of the attaching face of the top-lift stock at the points where the cutter operates. By maintaining the attaching face flush with one cutting boundary of the cutter, the body of the heel or the heel-cover, as the case may be, is safeguarded against damage even when the periphery of the top lift is being trimmed flush therewith. Moreover, by bracing the projecting margin of the attaching face of the top-lift where the cutter is in the stock being severed the production of rag or fuzz on the edge of the top lift is prevented.

To insure these desirable results some definite control of the relation between the trimming cutter and the articles of work is necessary. To this end, the invention also provides means for establishing and maintaining a flush relation between the attaching face of a top lift and one of the cutting boundaries of the trimming cutter, with provision for quickly and accurately making whatever adjustments may be necessary to counteract differences in the thicknesses of top lifts presented thereto.

In accordance with this aspect of the invention, the illustrated controlling means is designed to utilize each top lift in its turn, to regulate the cooperative relation between the trimming

cutter and a tread-rest according to the thickness of the top lift. In accordance with this feature of the invention, and as herein illustrated, two confronting and relatively adjustable gaging members may be provided. One of these may be a margin of the aforesaid tread-rest and the other a member by which the attaching face of an attached top lift may be located flush with the plane of the aforesaid cutting boundary of the trimming cutter. Upon inserting a projecting margin of an attached top lift between these gaging members the tread-rest and the trimming cutter may be adjusted, one relatively to the other, exactly in accordance with the thickness of the top lift, and by securing the relation thus established the controlling means is made ready to insure the safety of the heel or its cover from attack by the cutter.

Another feature of the invention comprises a trimming guide that projects slightly beyond the cutter in flush relation to the aforesaid cutting boundary thereof, the illustrated guide having a thin edge adapted to run in the crease between a heel and its top lift. The tread of the top lift is thus maintained against the tread-rest, the attaching face of the top lift is maintained flush with one cutting boundary of the cutter, and the stock being severed is braced against the cutter to insure clean cutting. Moreover, if the cutter is formed to bevel the tread of the top lift the trimming guide braces the margin of the top lift against lateral deflection by the beveling portion of the cutter.

Referring to the accompanying drawings,

Fig. 1 is a perspective view, partly broken away, of a trimming organization embodying the features hereinafter described;

Fig. 2 is a side elevation, partly in vertical section, of the trimming mechanism viewed from the right-hand side;

Fig. 3 is a side elevation, partly in section, of the tread-rest and means by which it may be adjusted in accordance with the thickness of an attached top lift;

Fig. 4 is a top-plan view including the trimming cutter, the tread-rest and the covered heel, the top lift of which occupies its preliminary gaging position by which the tread-rest is adjusted;

Fig. 5 is a vertical section of a portion of a covered heel and a portion of the tread-rest on a larger scale and includes a portion of the trimming cutter in the act of trimming the top lift; and

Fig. 6 is a view, partly in front elevation and partly in section, of the structure at the right of broken line VI—VI on Fig. 2.

The illustrated machine comprises a head or frame 10 mounted on the upper end of a supporting column or standard 12 intended to stand on a floor. The frame 10 is provided with bearings 14 for a horizontal cutter-shaft 16 having a pulley 18 to which high-speed rotation is communicated by a belt 20. The forward end of the cutter-shaft is provided with well known means for mounting and securing a toothed trimming cutter 22, the cutting edges of which are on its periphery and formed to determine the profile to be imparted to the top lifts. The axis of the cutter lies substantially at right angles to the plane of a tread-rest hereinafter described. The cutter is attached to the shaft by a screw 24 and a trimming guide consisting of a circular disk or plate 26, the latter being arranged in abutting relation to the front face of the cutter, that is,

in abutting relation to the front ends of the cutting edges thereof.

The illustrated tread-rest comprises a flat plate 28 arranged to tilt about two horizontal axes, one adjacent to the trimming locality and the other remote from that locality. At the remote axis the tread-rest is connected by horizontal trunnions 32 to a supporting member 34. The latter is connected by trunnions 36 to a vertically adjustable fixture 38, the axis of these trunnions being adjacent to the trimming locality.

As shown in Fig. 1, a screw 40 projecting from the upper portion of the member 34 is provided with a head that laps one edge of the tread-rest 28 to limit the range of free play or individual tilting movement of the tread-rest about the trunnions 32. The tread-rest is normally pressed forwardly against the head of the screw by a compression spring 42 (Fig. 2) enclosed in a socket 44 carried by the member 34, but, as hereinafter described, the tread-rest may be forced to the rear against the spring by pressure of a work-piece held against it. This feature of construction provides what may be termed a floating tread-rest.

The tread-rest may be adjusted about the axis of the trunnions 36 to determine the pitch or slant of the profile of a top lift in accordance with that of the heel to which the top lift is attached. For this purpose, the supporting member 34 is provided with an arm 46 in which a curved slot 48 is formed for the reception of a clamping bolt 50 the shank of which has screw connection with the adjustable fixture 38. Moreover, the tread-rest may be adjusted vertically to place its upper edge close to trimming cutters of various diameters. For this purpose, the supporting fixture 38 is connected by a clamping bolt 52 to a block 54, a vertical slot 56 (Fig. 6) in the member 38 providing a sufficient range of adjusting movement which may be conveniently effected by a thumb-screw 58.

The tread-rest is also adjustable horizontally, that is, in directions parallel to the axis of the cutter-shaft 16. For this purpose, the block 54 is secured by a bolt 59 to the forward end of a horizontal screw-shaft 60 arranged to slide in bearings in the frame 10, the rear end of the screw-shaft being provided with a screw-thread 50 and with a nut 62 for effecting adjusting movement. Turning movement of the screw-shaft 60 about its axis is prevented by a divided fixture 64 secured to the supporting column 12 and provided with confronting flanges 66 (Fig. 6) that embrace opposite vertical surfaces of the block 54. The fixture 64 is divided by a kerf 68 between the flanges 66 so that the flanges may be caused to clamp the block and thereby secure the member 38 rigidly with respect to the frame of the machine. For this purpose, the fixture 64 is provided with a clamping bolt 70. This fixture also supports the vertical adjusting screw 58.

Referring to Fig. 5 which represents portions of a covered heel, a trimming cutter, and the tread-rest on a magnified scale, satisfactory trimming of a top lift 12 requires locating its attaching face 74 in flush relation to the front face of the cutter 22. It rarely happens, however, that leather top lifts of a selected grade are, in fact, so nearly of uniform thickness as to bring about this flush relation when they are trimmed with the aid of a tread-rest that stands in the same position for all of them, since in every case the thickness of a top lift determines the plane in

which the attaching face will be guided to the cutter. Nevertheless, to counteract differences in thickness not only in top lifts made of leather but also in those made of other materials, the 5 present invention provides means by which the tread-rest may be quickly and accurately adjusted in accordance with the thickness of each top lift presented for trimming, to the end that the attaching face 74 of each top lift seated on 10 the tread-rest will lie in flush relation to the front face of the trimming cutter.

In Fig. 5, the body of a covered heel is indicated at 76 and the cover thereof is indicated at 78. In accordance with common practice, the 15 lower margin of the cover is folded over, prior to attaching the top lift, and laid on the bottom of the heel body 76 as shown in this figure. Subsequently, an oversize top lift is secured against the folded margin of the cover 78 by any suitable or preferred means, for example slugs 80, 20 driven through the top lift and into the heel body 76. If the top lift is made of leather, the flesh surface thereof will be the attaching face 74. At this stage of manufacture, the margin of the 25 top lift projects beyond the cover 78 as indicated at 82 and must be trimmed nearly, if not quite, flush with the cover to be acceptable to the trade.

To counteract non-uniformity of top lifts with 30 regard to their thickness, the trunnions 32 permit the upper portion of the tread-rest 28 to be adjusted toward and from the plane of the front face of the cutter 22, but the invention also includes means by which such adjustment may be 35 quickly and accurately effected and supplemental means by which it may be rigidly maintained while the individual top lift from which it was derived is being trimmed.

As shown in Fig. 1 the right-hand margin 84 40 of the tread-rest stands in confronting relation to a stationary abutment or gage represented as a plate 86 behind the lower portion of which a projecting margin 82 of a top lift may be inserted as shown in Fig. 3 and Fig. 4 without placing 45 any part of the top lift or its heel in the field or range of the cutter 22. The lower edge of the plate 86 lies in a horizontal plane tangent to the bottom of the cutter, and the rear face of the plate is flush with the vertical plane of the front 50 face of the cutter, although preferably it is beveled to facilitate inserting the top lift by moving the heel from right to left. After the desired cutter has been mounted on the shaft 16 the plate 86 may be adjusted to the front or to the 55 rear, if necessary, by turning the nut 62 (Fig. 2), but when once the rear face of the plate has been placed flush with the plane of the front face of the cutter it remains a constant from which the tread-rest may be adjusted in accordance with the thickness of each top lift presented thereto. On the other hand, it would be within a broad 60 aspect of the invention to reverse these conditions as by fixing the position of the tread-rest and combining the cutter and the gage 86 in an adjustable unit.

As shown in Fig. 3, the plate 86 is affixed by a 65 screw 88 to a bracket 90 rigidly secured to the member 34. The lower edge of the plate 86 is at the same level as the bottom of the cutter 22. The 70 gap between the plate 86 and the tread-rest is normally less than the thickness of the thinnest top lift, but whenever the tread-rest is forced back by a top lift the margin of which is inserted behind the plate 86, the operator permits the 75 tread-rest, under the influence of the spring 42, to

press the top lift against the plate. Thus, the tread-rest is located at a distance from the plane of the front face of the cutter 22 exactly equal to the thickness of the top lift, as shown in Fig. 3 and Fig. 4.

Before removing the top lift from its gaging position, the operator locks or clamps the tread-rest in the position to which it has been adjusted with regard to the thickness of the top lift, and, having secured the tread-rest in this position, he shifts 10 the heel laterally to the trimming cutter and proceeds with the manipulation necessary to trim the top lift flush with the cover of the heel. Further details of the trimming operation are hereinafter described.

To secure and release the tread-rest in operative positions variously distant from the plane of the trimming guide 26, the illustrated machine is provided with clamping means including a treadle 92 (Fig. 1) and a train of connections operated thereby. A horizontal rod 94 connected to the upper portion of the tread-rest by a pivot pin 96 extends to the rear and lies on a block 98 with which a lever 100 cooperates to clamp it. The lever 100 is connected to the treadle 92 by a rod 106 and is normally raised by a tension spring 108 the lower end of which is connected to the treadle and 30 the upper end of which is connected to a collar 100 adjustably secured to a supporting post 112. This post is affixed to a split ring 114 designed to surround the lower portion of the floor standard 12 and to be rigidly clamped thereto. A stud 116 35 carried by the ring 114 serves as a fulcrum for the treadle 92. The connection between the treadle rod 106 and the clamping lever 100 includes a compression spring 118 that permits the treadle to be depressed to the floor without subjecting the clamping mechanism to excessive strain. This spring is seated on the upper side of the lever 100 and is held under initial compression by a collar 120 adjustably secured to the rod 106 by a set-screw. When the treadle is 40 raised by the spring 108 the clamping lever 100 is likewise raised by a collar 122 adjustably secured to the rod 106 by a set-screw. With this mechanism, the operator has merely to depress the treadle 92 to maintain the tread-rest 28 in the 45 position to which it has been adjusted in accordance with the thickness of a top lift, the rod 94 connected to the tread-rest being initially free to slide forward and back under the clamping lever 100 while the tread-rest is being adjusted.

Referring to Fig. 5, the margin of the circular disk 26 projects slightly beyond the periphery of the cutter 22 and is so thin as to enter the seam or crease between a top lift and a folded-in margin of a heel cover 78. The magnitude of projection of the disk is so slight and the projecting portion is so thin that no appreciable effort is required to maintain the edge of the disk in the crease. The outer surface of the disk is preferably beveled to facilitate insertion of the projecting portion, but the rear face of the disk is preferably flat since it is desirable that this face shall lie in the same plane as the front face of the cutter.

When once the tread-rest has been adjusted in 70 accordance with the thickness of a top lift and secured by means of the clamping lever 100, as hereinbefore described, accurate trimming of the top lift is assured, since the tread-rest stands in a position that will maintain the attaching face of 75

the top lift in flush relation to the front face of the cutter. When a heel is shifted laterally from the gaging element 88 to the trimming cutter, the tread-rest will guide the tread surface of the top lift so that the projecting edge of the disk 26 will lap the margin of the top lift and engage the attaching face thereof. The cutter 22 trims away the surplus margin of the top lift with cuts that progress lengthwise of the periphery, and the projecting edge of the disk 26 runs in the crease as shown in Fig. 5, meanwhile bracing the attaching face of the top lift stock being severed by the cutter so that clean trimming of the top lift is assured.

15 When, as shown in Fig. 5, the cutter is provided with an inclined lip 23 for beveling the tread-face of a top lift, the lip tends to deflect the top lift away from the tread-rest and thereby displace the attaching face of the top lift from the plane of the front face of the cutter. Nevertheless, since the attaching face is braced by the projecting margin of the disk 26 it is maintained against the displacing tendency. Consequently, the tread-face will be beveled rather than deflected by the lip 23. This bracing of the attaching face of the top lift by the disk 26 is particularly advantageous when trimming top lifts made of leather but is not without a corresponding advantage when trimming top lifts made of other materials. In any event, as the heel is turned while in contact with the cutter it is guided not only by its tread surface but also by its attaching face, since the tread-rest and the projecting portion of the disk 26 cooperate with each other to maintain the attaching face of the top lift in flush relation to the front face of the cutter.

20 To regulate the depth of the cut so that the trimmed surfaces of the top lift will be flush or nearly flush with the heel cover 78, the machine is provided with a stationary adjustable trimming gage 130 (Fig. 2) arranged to run on the cover. This gage is arranged in front of and close to the disk 26. It is supported by a bracket 132 to which it is clamped by a bolt 134 and a plate 136, a slot 138 being formed in the gage to provide for vertical adjustment thereof. The upper margin of this gage is provided with a horizontal groove for the reception of a flange 140 formed on an adjusting screw 142. This screw is threaded in the bracket 132. Provision is also made for adjusting the gage 130 horizontally so that it may be placed close to the disk 26 without quite touching the latter. For this purpose, the rear end of the bracket 132 is adjustably connected to the frame 10 by a clamping bolt 144 which extends through a slot 146 in the bracket and is screwed into the frame. Tongue-and-groove formations indicated collectively at 148 are formed on the bracket and on the frame respectively to prevent the bracket from turning about the clamping bolt 144.

25 Having thus described the invention, what I claim as new and desire to secure by Letters Patent of the United States is:

60 1. That improvement in methods of controlling the trimming of top lifts which consists in moving a heel and an attached top lift and thereby relatively adjusting a trimming cutter and a tread-rest in a cooperative relation according to the thickness of the top lift, fixing such cooperative relation while it is maintained by the top lift, and trimming the top lift with the cutter and with the aid of the tread-rest while such cooperative relation is fixed.

65 2. That improvement in methods of trimming

top lifts attached to heels, which consists in moving a heel and thereby causing the projecting margin of an attached top lift to establish a spaced relation, commensurate with the thickness of said margin, between a tread-rest and the plane of one cutting boundary of a trimming cutter without placing the top lift against the cutter, securing the spaced relation thus established, and relatively moving the work and the cutter in such a manner as to trim the periphery of the top lift flush with the body of the heel while maintaining the tread of the top lift against the tread-rest.

70 3. That improvement in methods of trimming top lifts attached to heels, which consists in moving the attaching face of a projecting margin of an attached top lift into the plane of one cutting boundary of a trimming cutter and thereby causing the top lift to adjust the cutter and a tread-rest relatively one to the other in accordance with the thickness of the top lift, bracing said face in said plane, securing the relation of the cutter and the tread-rest thus established while said attaching face is being braced as aforesaid, and maintaining the top lift against the tread-rest by bracing the attaching face of said margin while relatively moving the work and the cutter to trim the periphery of the top lift.

75 4. A trimming machine comprising a rotary driven cutter arranged to trim the periphery of a top lift attached to a heel, a gaging member spaced radially from said cutter but maintained rigidly in flush relation to the plane of one end of the cutter, a relatively wide gaging member one portion of which confronts the first said gaging member and another portion of which is cooperatively related to said cutter to serve as a tread-rest while the cutter trims the top lift, one of said gaging members being movable toward and from the other to gage the thickness of the top lift, and means arranged to secure and release the movable gage in various thickness-gaging positions.

80 5. A trimming machine comprising a rotary driven cutter arranged to trim the periphery of a top lift attached to a heel, a fixed abutment spaced radially from said cutter and arranged in flush relation to the plane of one end of the cutter, a tread-rest one portion of which is cooperatively related to said cutter and another portion of which confronts said abutment, said tread-rest being freely adjustable toward and from said plane to gage the thickness of a projecting margin of a top lift interposed between it and said abutment, and manually operative means arranged to secure and release the tread-rest in various thickness-gaging positions.

85 6. A trimming machine comprising a rotary driven cutter arranged to trim the periphery of a top lift attached to a heel, a trimming guide arranged against the front face of said cutter and projecting radially beyond the periphery of the cutter to guide the top lift by its attaching face, a yieldable tread-rest normally impelled toward the plane of said front face, and means controllable manually at will to secure and release said tread-rest in positions of adjustment variously distant from said plane according to the thicknesses of top lifts presented for trimming.

90 7. A top-lift-trimming machine comprising a rotary trimming cutter, a thin-edged shield arranged against the front face of said cutter to engage the attaching face of an attached top lift, a tread-rest adjustable toward and from the plane of said shield, a fixed gage confronting the

tread-rest at one side of said cutter, said gage being flush with the plane of said shield, and means arranged to secure the tread-rest in various positions of adjustment according to the 5 thicknesses of top lifts inserted between the tread-rest and said gage.

8. A top-lift-trimming machine comprising a rotary trimming cutter, an adjustable tread-rest normally spring-pressed toward the plane of the 10 front end of said cutter, an abutment confronting the front face of the tread-rest, said abutment being flush with said plane, and means arranged to secure the tread-rest against the tread of an attached top lift of which the attaching 15 face lies against said abutment.

9. A top-lift-trimming machine comprising a rotary trimming cutter, an adjustable tread-rest normally spring-pressed toward the plane of the front end of the cutter, frictional means operative 20 manually to secure the tread-rest in positions of adjustment variously distant from said plane, and means arranged to locate the attaching face of an attached top lift flush with said plane.

10. A top-lift-trimming machine comprising a 25 rotary unit including a trimming cutter and a circular trimming guide rigidly maintained in abutting and concentric relation, the margin of said guide projecting radially beyond the periphery of the cutter and being so thin as to run in the 30 crease between a covered heel and a top lift attached thereto, a yieldable tread-rest normally impelled toward the plane of said guide, and means controllable manually at will to secure and release said tread-rest in positions of adjustment variously distant from said plane according to the thicknesses of top lifts presented for trimming.

11. A top-lift-trimming machine comprising a trimming guide arranged to engage a projecting 40 margin of the attaching face of a top lift attached to a heel, a yieldable tread-rest normally impelled toward the plane of said guide, means controllable manually at will to secure and release said tread-rest in positions of adjustment variously distant from said plane, a power-operated cutter arranged to trim a top lift inserted between said tread-rest and said guide, and means arranged in caliper relation to a portion of said tread-rest radially distant from said 45 cutter to establish the operative position of the tread-rest by a top lift inserted between it and the tread-rest.

12. A top-lift-trimming machine comprising a rotary trimming cutter, a trimming guide having a thin margin arranged to function by engagement with the confronting faces of a heel and an attached top lift, an adjustable tread-rest 5 normally spring-pressed toward the plane of said trimming guide, and means arranged to secure said tread-rest in positions of adjustment variously distant from said plane to maintain the attaching faces of top lifts of various thicknesses 10 against said guide.

13. A top-lift-trimming machine comprising a trimming cutter, a tread-rest adjustable about one axis to determine the pitch or slant of the profile of a top lift and about another axis to 15 locate the attaching face of the top lift in flush relation to one cutting boundary of said cutter, and means for securing the tread-rest in various positions of adjustment.

14. A top-lift-trimming machine comprising a 20 trimming cutter, a tread-rest adjustable about two parallel axes one of which is adjacent to the cutter and the other remotely located, means for securing the tread-rest with respect to angular adjustment about one of said axes, and independent 25 means for securing the tread-rest with respect to angular adjustment about the other one of said axes.

15. A top-lift-trimming machine comprising a trimming cutter, a tread-rest, an angularly adjustable support by which said tread-rest is carried, means for securing said support in various positions of angular adjustment to regulate the pitch of the trimmed profile of a top lift, the tread-rest being adjustable relatively to said support according to the thickness of a top lift, and 35 treadle-operated means arranged to secure and release the tread-rest.

16. A top-lift-trimming machine comprising a rotary trimming cutter, an upstanding yieldable 40 tread-rest in a plane approximately at right-angles to the axis of said cutter, a work-gage confronting the tread-rest, the tread-rest being normally impelled toward said work-gage, and treadle-operated means arranged to secure and 45 release the tread-rest in operative positions variously distant from said gage according to the thicknesses of top-lifts inserted between the gage and the tread-rest.

NORWOOD H. KNOWLTON.
